UNITED STATES PATENT OFFICE.

GEORGE HERBERT BUTTERWORTH AND ROWLAND CANLIN, OF GREAT CROSBY, NEAR LIVERPOOL, ENGLAND.

FIRE-BRIDGE FOR BOILER OR THE LIKE FURNACES.

1,137,048.

Specification of Letters Patent. Patented Apr. 27, 1915.

Application filed May 4, 1912. Serial No. 695,258.

To all whom it may concern:

Be it known that we, GEORGE HERBERT BUTTERWORTH and ROWLAND CANLIN, subjects of the King of Great Britain, and residing at Great Crosby, near Liverpool, in the county of Lancaster, England, have invented certain new and useful Improvements in Fire-Bridges for Boiler or the like Furnaces, of which the following is a specification.

This invention has reference to fire bridges of the hollow type adapted to admit air from the ash-pit into the space above or beyond the fire bars, the object being to simplify and cheapen the construction and to so arrange the component parts that cleaning and renewals may be effected expeditiously and cheaply.

According to our present invention the perforated part of the bridge is carried by a rectangular base plate, and is built up of a number of sectional arch pieces carried on a slide or bed attached to the base plate. The arch-pieces are identical in shape and are of such configuration that when assembled, they form with two end plates, a complete hollow perforated arch, the perforations being formed between the successive arch pieces. Each arch piece may form a complete section of the arch, or there may be two arch pieces, one at the back and one at the front to form the complete section, in which case there are overlapping parts of half thickness. Each arch piece has a dove-tail extension which fits in a dove-tail groove in the slide or bed, the arrangement being such that the dove-tail extensions serve to hold the arch pieces in position on the bed.

One important feature of the present invention is, that if the arched part of the sectional arch pieces burns away there is no increase in the available air passages, these remaining constant as the arch-pieces are burnt away.

It will be seen that a bridge built up of arch pieces which are identical in shape offers great advantages in respect to renewal, since there is practically but the one kind of spare part to be stocked, and that this part can be used to renew any section of the bridge arch; and as the perforations are formed by coinciding recesses in the sectional arch pieces all the perforations

may be divided laterally for cleaning, by a slight lateral separation of the arch pieces.

The invention, as applied to the furnace, of say, a marine boiler, is illustrated in the accompanying drawings, in which,

Figure 1 is a longitudinal view showing the bridge in position in the furnace, Fig. 2 being a corresponding transverse section on the line II, II, of Fig. 1. Fig. 3 is a plan of the bridge, to a larger scale, the sectional arch-pieces being omitted from the right hand side, and some of the front halves of these being omitted from the left hand side; Fig. 4 is a corresponding elevation, the right hand half being in section on the line IV, IV, of Fig. 3, and showing the right hand end section in position. Fig. 5 is an end elevation and Fig. 6 a corresponding end elevation in section on the line VI, VI, of Fig. 3. Figs. 7 and 8 are fragmentary sections on the lines VII, VII, and VIII, VIII, of Fig. 4. Figs. 9 and 10, and 9^A and 10^A are respectively elevations and plans of front and back sectional arch pieces shown apart, Fig. 10^B being a side view of Fig. 10. Figs. 11 and 12 are an elevation, and a plan of these two pieces assembled together, and Fig. 13 is an elevation similar to Fig. 11, but to a larger scale of two of the sectional arch pieces assembled together, Figs. 14 and 15 being corresponding sections on the lines XIV, XIV, and XV, XV, of Fig. 13. Fig. 15^A shows a modification.

The base-plate A is in the form of an open rectangular frame which is fitted transversely across the furnace, being fixed in position by the lugs a¹; the base-plate has a ledge a² to take the ends of the fire-bars B, and it is usually fitted with a depending plate C provided with door c¹ to permit ashes being raked out from behind the bridge. To the base-plate is fixed a slide or bed D, which in the example illustrated is made in the form of two side rails secured to the base plate by the lugs d¹ each side rail being made in two lengths joined at the lugs d². Each rail is framed to form a series of openings d³, and the inner bar d⁴ of each rail forms, with the corresponding bar of the other rail, a dove-tail slot d⁵ the beveled edges of the rails forming the dove-tail being cut away at each end as shown at d⁶.

E are the sectional arch pieces, they are shaped as shown, and are assembled by disposing them adjacently and alternately to front and rear; distance facings e^1 abut together and the recesses form passages e^2 ; the overlapping dove-tail extensions e^3 locate the pieces in the dove-tail slot d^5 , the sloping lower edges of the pieces resting on the sloping parts of the rail d^4 . The pieces are inserted in the dove-tail slot at the cut away ends where the latter widen out and are then slid along till the dove-tail engages. Fig. 8 shows, in section, the arch piece being inserted, and Fig. 7 shows it in position in the dove-tail.

The central overlapping parts e^4 of the sectional arch pieces are half the thickness of the unperforated parts so that when the pieces are assembled air can pass as shown by the arrow-heads in Figs. 6 and 13: Two end plates F are fitted which are hollowed on the outside face so as to facilitate shaping to fit the interior contour of the furnace. It will be seen that if the sectional arch pieces burn away, even down to the line P, Q, Fig. 13 there will be no material increase in the cross sectional area of the air passages through the bridge since the remaining central parts e^4 maintain this area practically constant.

The arrangement illustrated is as stated one designed for furnaces in boilers of the marine type, but the details of the invention can be modified within the limits of the invention to suit particular requirements. For instance, while it is found most convenient to make the section arch pieces in halves with overlapping central portions of half thickness, the two halves may obviously be made integral as shown in the right hand arch piece of Fig. 14 and in Fig. 15^A which is a view analogous to Fig. 15; the shape of the sectional arch pieces may also be modified to give a different section of hollow bridge, the distance pieces being arranged to suit the perforations required for such section; and the slide or bed may be made integral with the base plate and it and the corresponding part of the sectional arch-pieces may be modified in shape to give any suitable mode of connection of the sectional arch pieces to the base plate.

Having now fully described our invention, we declare that what we claim, and desire to secure by Letters Patent is:—

1. In a fire bridge, in combination, a pair of rails extending across the furnace, supporting means therefor, an arch formed of a series of arch pieces each consisting of two sections, each of said arch pieces comprising a web, which in transverse elevation is co-extensive with the arch piece as a whole, and a series of distance facings on each side of the web adapted, when the arch pieces are assembled to form the arch, to abut and

form air-ways between the webs, substantially as described.

2. In a fire bridge, in combination, a pair of rails extending across the furnace, supporting means therefor, an arch formed of a series of arch pieces each consisting of two sections, each of the said arch pieces comprising a web, which in transverse elevation is coextensive with the arch piece as a whole and which is provided with a depending extension adapted to engage with the rails, and a series of distance facings on each side of the web adapted, when the arch pieces are assembled to form the arch, to abut and form air-ways between the webs, substantially as described.

3. In a fire bridge, in combination, a pair of rails extending across the furnace, supporting means therefor, an arch formed of a series of arch pieces each consisting of two sections, each of said arch pieces comprising a web, which in transverse elevation is co-extensive with the arch piece as a whole, and a series of distance facings on each side of the web located so as to leave a margin of web outside the facings, said distance facings being adapted, when the arch pieces are assembled to form the arch, to abut and form air-ways between the webs, substantially as described.

4. In a fire bridge, in combination, a pair of rails extending across the furnace, supporting means therefor, an arch formed of a series of pairs of overlapping sections each of which extends across and is carried by perforated extensions on the rails, each pair of overlapping sections forming an arch piece comprising a web extending from the periphery of the arch to the extensions, and a series of thin distance pieces on each side of the web, the distance pieces of adjacent arch pieces being in contact and leaving parallel air-ways between the arch pieces, substantially as described.

5. In a fire bridge, in combination, a pair of rails extending across the furnace, supporting means therefor, an arch formed of a series of pairs of overlapping sections each of which extends across and is carried by perforated extensions on the rails, the edges of said extensions forming a dove-tail recess and the said overlapping parts being shaped to form a dove-tail attachment piece fitting said recess, substantially as described.

6. In a fire bridge, in combination, a pair of rails extending across the furnace, supporting means therefor, an arch formed of a series of pairs of overlapping sections each of which extends across and is carried by perforated extensions on the rails, each pair of overlapping sections forming an arch piece comprising a web extending from the periphery of the arch to the extensions, and a series of thin distance pieces on each side of the web, said distance pieces being located

on the webs so as to leave a margin of web outside the distance pieces, substantially as described.

7. In a fire bridge, in combination, a pair of rails extending across the furnace, supporting means therefor, an arch formed of a series of pairs of overlapping sections each of which extends across and is carried by perforated extensions on the rails, each section having a central part of triangular configuration and of reduced thickness, said parts of opposite sections of a pair being adapted to overlap and form the center of the web of an arch piece, substantially as described.

8. In a fire bridge, in combination, a pair of rails extending across the furnace, supporting means therefor, an arch formed of a series of pairs of overlapping sections each of which extends across and is carried by perforated extensions on the rails, each section having a central part of triangular configuration and of reduced thickness provided with a dove-tail attachment extension, said parts of opposite sections of a pair being adapted to overlap and form the center of the web of an arch piece, substantially as described.

9. In a fire bridge, in combination, a pair of rails extending across the furnace, supporting means therefor, an arch formed of a series of pairs of overlapping sections each of which extends across and is carried by

perforated extensions on the rails, the rear side of the arch being formed of sections 35 separate from but identical in shape with and interchangeable with those forming the front side, substantially as described.

10. In a fire bridge, in combination, a pair of rails extending across the furnace, 40 supporting means therefor, a series of arch pieces provided with centrally located dove-tail depending lugs, said rails having internally projecting extensions provided with passage-ways and adapted to form a bed 45 for the sectional arch pieces and to engage said depending lugs, the said extensions being cut away at the ends of the rails, substantially as described.

11. In a fire bridge, in combination; the 50 sectional arch pieces; the transverse rails having internal perforated extensions, and supporting means for the rails, said perforated extensions forming a bed with reversely sloped sides, said sectional arch pieces having correspondingly sloped webs with dove-tailed extensions resting on and fitting said reversely sloped sides of the bed, substantially as described.

In testimony whereof we affix our signatures in presence of two witnesses.
